PAUL H. HORWITT, OF BROOKLYN, NEW YORK, ASSIGNOR TO INDEPENDENT PAPER MILLS INC., OF BROOKLYN, NEW YORK, A CORPORATION OF NEW YORK.

DISPENSER FOR NAPKINS AND LIKE ARTICLES

Application filed July 21, 1923. Serial No. 652,941.

To all whom it may concern:

Be it known that I, PAUL H. HORWITT, a citizen of the United States, residing in the borough of Brooklyn, county of Kings, city 5 and State of New York, have invented an Improvement in Dispensers for Napkins and like Articles, of which the following is a specification.

This invention relates to an improvement 10 in dispensers for paper napkins and similar articles. Heretofore as I am aware, various forms of dispenser for napkins, towels and like articles made of paper and similar material have been employed, the dispensers 15 being so constructed and the napkins, towels or other articles being so bundled and placed in the dispenser as to provide for the user taking but one napkin or towel at a time in order, as will be understood, to effect 20 economy in the use of the articles. In some types of dispensers of this class, for example, the construction is such as to receive the bundle of napkins superimposed in a pile 25 in which alternate napkins are placed transversely, that is crosswise and maintained in position by a retainer through which the transversely placed articles may be withdrawn one at a time. In other types of these containers the napkins or other articles 30 have been placed in a superimposed pile with the end portion of either the uppermost or the lowermost article so maintained in position that it may be readily grasped and the article withdrawn endwise from 35 the pile. As another example, dispensers of this type have been made to receive a bundle of napkins or towels so folded as to have a portion of the outermost article extend through an aperture in the dispenser, while 40 the napkins or towels in this instance are so interlapped that by withdrawing the outermost article a portion of the next succeeding article is also withdrawn through the aperture in the dispenser. In no instance, however, to which my attention has been directed has there ever been provided a napkin, towel or other similar article so folded 45 that when grasped and raised, either being taken from a pile or from a dispenser, the article is unfolded or open for use. Nor so far as I am aware has any provision heretofore been made for a dispenser for containing articles folded as hereinbefore indicated and in assisting the unfolding of the article 50 when being withdrawn or taken from the

dispenser. The object of my present invention, therefore, is the provision of a dispenser adapted to receive and contain a superimposed pile of napkins, towels or other articles, each of which is so folded 60 that it may be readily grasped by the user and withdrawn from the dispenser and in the act of so doing the article is unfolded or open for use. The dispenser made in accordance with the invention also includes 65 means for normally maintaining the napkins or other similar articles therein and to assist the unfolding or opening of the same in withdrawing them from the dispenser one at a time as will be hereinafter more particularly described. 70

In the drawing:

Fig. 1 is a perspective view illustrating a type of dispenser made in accordance with my present invention and showing the manner in which a napkin or other article as taken therefrom is unfolded. 75

Fig. 2 is a plan of a blank from which a napkin or other article adapted for use in the dispenser is made. 80

Fig. 3 is a perspective view of the napkin or other article as folded. 85

Fig. 4 is a perspective view of a bundle of napkins or towels. 90

Fig. 5 is a transverse sectional elevation of the dispenser as shown in Fig. 1. 95

Fig. 6 is a perspective view of the retainer frame as used in the form of dispenser shown in Figs. 1 and 5. 100

Fig. 7 is a partial side elevation of another form of dispenser. 105

Fig. 8 is a section on line 8—8, Fig. 7.

Fig. 9 is an elevation of the retainer member used in the form of the invention as shown in Figs. 7 and 8. 110

Fig. 10 is an end elevation of another form of dispenser, and

Fig. 11 is a plan of the retainer frame employed in the form of the dispenser shown in Fig. 10. 115

The napkin or other article adapted for use with the dispenser made in accordance with this invention is illustrated in Figs. 1, 2, 3 and 4. By reference to these figures and particularly to Fig. 2, it will be seen 105 that the napkin or other article of paper or other material to be used in the dispenser may be folded from a sheet of any predetermined size. This sheet is folded along predetermined substantially parallel lines 110

indicated at 10 and 11, 12 and 13, 14 and 15 and 16 and 17. The lines 10 and 11 are substantial continuations of each other as are the lines 12 and 13, the lines 14 and 15 and the lines 16 and 17. In the blank as indicated in Fig. 2, there is also a centrally disposed fold line 18 at right angles to the fold lines hereinbefore described and to which reference will be hereinafter made. When the sheet is provided with these fold lines it is divided into a plurality of sections indicated at 19 and 20, 21 and 22, 23 and 24, 25 and 26 and 27 and 28. As illustrated the sections are folded in one direction along the lines 10 and 11 so that the obverse faces of the sections 19, 20, 21 and 22 come together; the sections are then folded in the reverse direction along the lines 12 and 13 so that the reverse faces of sections 21 and 22 are juxtaposed to the reverse faces of the sections 23 and 24 respectively. Then again the sections are folded in the other direction along the lines 14 and 15 so that the obverse faces of sections 23 and 24 are juxtaposed to the obverse faces of sections 25 and 26, and then the fold along the lines 16 and 17 is again made in an opposite direction so that the reverse faces of the sections 27 and 28 lie against the reverse faces respectively of the sections 25 and 26. When the sheet is thus folded it forms a relatively long rectangular article which is then folded transversely along the fold lines indicated at 18 in the blank to assume the form of the napkin or towel or other article as illustrated in Fig. 3 of the drawing.

It will be noted that in thus folding the sheet to form a napkin, towel or other article there is provided therein a plurality of inner or centrally disposed coextensive sections 21 to 26 inclusive and end sections 19 and 20 and 27 and 28 which are appreciably smaller than the other sections. As illustrated these end sections are of substantially one-half the width of the intermediate sections, but as will be understood they may be of any desired and predetermined width. It will also be understood that any desired number of central or intermediate sections may be employed and that the number as shown is merely illustrative. Furthermore in carrying out the invention it is not necessary to employ the non-coextensive sections at both ends of the blank, as but one of them will answer all intents and purposes in some instances. The advantage, however, in employing the non-coextensive sections at both ends of the blank is that thereby it is immaterial in which direction the parts are folded on the fold line 18 because in either event, that is whether folded in one direction or the other there will be an outer non-coextensive section, the edge of which may be grasped

in taking the napkin or other article for use.

This article, as hereinbefore described, whether a towel, napkin or some other article is preferably bundled as indicated in Fig. 4, the superimposed pile being designated at 29 and the tape or cord by which the pile is bundled designated at 30.

The napkins, towels or other articles folded and bundled as hereinbefore described are placed in a suitable dispenser from which they may be withdrawn for use. This dispenser may assume one of any number of constructions. For example, as shown in Figs. 1, 5 and 6, the dispenser may comprise a body member having oppositely disposed ends 31 and 32 and intermediate side members 33 and 34, together with a bottom or support 35 and suitable feet 36 and 37. As illustrated in this form of the invention the side members 33 and 34 are correspondingly recessed as indicated at 38 and 39 to facilitate the withdrawal of the contents from the container. As will be understood the container is open at the top and may be made of glass, metal or other similar and suitable material in the configuration described or in any other suitable form adapted to serve the purposes of the invention. In this form of dispenser and as illustrated in these figures of the drawing I employ a retainer frame comprising rolls 40 and 41 and cross bars 42 and 43 secured at their ends to the extremities of the rolls by pivot screws 44 and 45 or otherwise. This retainer frame is made to conform to the inside dimensions of the dispenser, that is to say the distance between the outside edges of the rolls 40 and 41 is substantially the width of the dispenser, and the distance between the outer faces of the cross bars 42 and 43 is substantially the inside length of the dispenser so that the retainer frame may be easily removed and replaced in the dispenser after the bundle of napkins or towels has been placed therein to normally retain the superimposed articles comprising the bundle in position. In so doing, as will be understood, the rolls 40 and 41 bear against the long folded edges of the articles and the free edge of the outermost section or fold as indicated at 46 of the uppermost article is entirely free inasmuch as the cross bars 42 and 43 are preferably curved so as to leave this edge of the section free even at the ends thereof. It will be understood that the dispenser is made with predetermined inside dimensions so as to receive a bundle or bundles of napkins or other articles folded to a predetermined size. In practice the preferred size of the folded article is substantially $3\frac{1}{2} \times 7$ inches, and the inside dimensions of the dispenser are the same or slightly in excess of these dimensions. It will furthermore be understood that when the outer

section of the uppermost article in the dispenser is grasped and removed for use the article will be unfolded and by withdrawing the article from beneath the rolls 40 and 41 the unfolding or opening of the article is enhanced inasmuch as naturally due to the tension placed on the outermost non-coextensive section the edges of this and the adjacent section are first withdrawn from beneath the roll 40 and then from beneath the roll 41 and this action is substantially continued, withdrawing portions of the article first from one side and then the other until it is completely removed from the dispenser.

15 The retainer frame as shown in the form of the invention illustrated in Figs. 1, 5 and 6 is an integral structure entirely removable from and replaceable in the body of the dispenser. In some instances, however, it may 20 be advisable to provide the dispenser with a retainer member or members which are so associated therewith as to perform their function of normally maintaining the superimposed articles in position and adapted to 25 be shifted to an exterior position to permit the dispenser to be refilled readily. In Figs. 7, 8 and 9, it will be seen that to this end the side members of the dispenser adjacent the ends thereof may be provided with slots 30 47 and independent retainer rods 48 employed. Each of these retainer rods is adapted to fit within the dispenser and to extend longitudinally thereof. Adjacent the ends of each of these retainer rods the same is 35 fitted with a pin 49 having a ball or round head 50, the pins being secured in the rod in any desired manner. Each pin 49 is passed through a slot 47 and then secured in the rod. In this form of the invention the 40 side members at the upper portions thereof are each provided with flanges 51, each flange having a retaining recess 52 into which, as shown in Fig. 8, an end portion of the corresponding retainer rod may be 45 placed and supported when, for example, it is desired to place a new bundle of napkins or other articles in the dispenser, it being understood furthermore that there is one of these rods 48 on each side of the 50 dispenser.

As illustrated in Figs. 10 and 11 a somewhat similar construction may be employed in which an end of the dispenser is provided with slots 53 and a retainer member 55 employed which comprises rods 54 and 55 with an end or cross piece 56 connecting them at corresponding ends, while the opposite ends are fitted with pins 57 having ball or round heads 58. This retainer member 60 is also adapted to fit within the dispenser and the pins 57 pass through the slots 53 and then to be secured in any suitable manner in the corresponding adjacent ends of the rods. In this form of the invention the 65 slotted end of the dispenser is provided with

a flange 59 having a retaining recess 60 therein into which the ends of the rods 54 and 55 may rest when the retainer member is swung to a position exterior of the dispenser to enable the user to refill the dispenser by placing therein a new bundle of napkins, towels or similar articles.

From the foregoing description it will now be understood that the various forms of dispensers illustrated and described are 75 merely illustrative of my invention inasmuch as the dispenser made in accordance therewith may be made in any suitable manner to include a retainer device of any construction adapted to cooperate with the 80 uppermost or outermost napkin, towel or other article placed in a superimposed bundle in the dispenser to assist in the self-opening or unfolding of the napkin or towel when withdrawn from the dispenser. the napkins, 85 towels or other articles for this purpose being folded in the manner hereinbefore described. It will also now be apparent that the dispenser may be made in a predetermined and uniform size and thus adapted to 90 receive sheets of any desired original size folded and superimposed in bundles of predetermined numbers to be placed in and dispensed from the dispenser. It will furthermore be understood that while the invention as hereinbefore shown and described 95 relates particularly to a dispenser from which napkins, towels or other articles are taken from the top thereof that the dispenser may be placed in any suitable position and the retaining member provided with resilient or other means for normally maintaining the same in position in the dispenser to cooperate with the articles therein when such a construction is necessary or desirable. 100

I claim as my invention:

1. In a device for dispensing paper napkins, towels and like articles, a body member adapted to receive a package of superimposed articles each folded from a sheet of 110 material into a plurality of substantially coextensive centrally disposed sections, and an end section which is outermost and non-coextensive with the other sections, and members extending interiorly along opposite 115 sides of the body member and adapted normally to rest upon the oppositely folded edge portions of the said folded articles, the space between the said members being entirely open within the body member leaving the edge of the non-coextensive section of the outermost folded article entirely free to be grasped for removing the same.

2. In a device for dispensing paper napkins, towels and the like, a rectangular receptacle open at one end and adapted to receive a package of superimposed articles each folded from a sheet of material in oppositely disposed directions into a plurality 125 of substantially co-extensive centrally dis- 130

- posed sections, and an end section which is outermost and non-coextensive with the other sections, and rolls fitting within the said receptacle and extending from end to end thereof and adapted normally to rest upon the oppositely disposed folded edge portions of the said articles therein leaving the entire space open between the said rolls to make the free edge of the non-coextensive 10 section of the outermost article entirely free to be grasped for the removal of the same.
3. In a device for dispensing paper napkins, towels and like articles, a receptacle open at one end and adapted to receive a 15 package of superimposed articles each folded from a sheet of material in oppositely disposed directions into a plurality of substantially coextensive centrally disposed sections and an end section which is outermost and non-coextensive with the other sections, rolls fitting within the said receptacle and extending from end to end thereof and adapted to bear against the oppositely disposed folded edge portions of the said articles, the entire space between the said rolls being open to make the edge of the said non-coextensive section of the outermost article entirely free to be grasped for the removal of the said outermost article,
- 20 means whereby the said rolls are shiftable
- to the exterior of the receptacle, and means for supporting the said rolls when outside of the receptacle.
4. In a device for dispensing paper napkins, towels and like articles, a receptacle 35 open at one end and adapted to receive a package of superimposed articles each folded from a sheet of material in oppositely disposed directions into a plurality of substantially coextensive centrally disposed sections and an end section which is outermost and non-coextensive with the other sections, rolls fitting within the said receptacle and extending from end to end thereof and adapted to bear against the 40 oppositely disposed folded edge portions of the said articles, the entire space between the said rolls being open to make the edge of the said non-coextensive section of the outermost article entirely free to be grasped 45 for the removal of the said outermost article, the walls of the said receptacle being provided with slots, pins connected to the said rolls and extending through the said slots, and a support on the walls of the 50 said receptacle for receiving each roll when the roll is removed therefrom.

Signed by me this 20th day of July, 1923.

PAUL H. HORWITT.
